UNITED STATES PATENT OFFICE.

THOMAS FENWICK, OF MOBILE, ALABAMA.

SHIP-HULL CONSTRUCTION.

1,240,129.

Specification of Letters Patent. Patented Sept. 11, 1917.

Application filed October 3, 1916. Serial No. 123,533.

To all whom it may concern:

Be it known that I, THOMAS FENWICK, a citizen of the United States, residing at Mobile, in the county of Mobile and State of Alabama, have invented new and useful Improvements in Ship-Hull Constructions, of which the following is a specification.

This invention relates to marine vessels and particularly to the hull construction, the object in view being to produce a strong, efficient and leak proof hull structure made up of steel or iron and concrete combined, the metal parts of the structure being so arranged relatively to each other and to the frame and other parts of the hull, and the concrete having such relation to the metal parts, that a thoroughly rigid, strong and enduring hull structure is obtained, the same being comparatively light and of less thickness than the ordinary present day hull structure, producing a smooth exterior and interior surface and increasing the carrying capacity of the hold.

With the above and other objects in view, the invention consists in the novel construction, combination and arrangement herein fully described, illustrated and claimed.

In the accompanying drawings:—

Figure 1 is a plan view partly in section of a hull structure embodying the present invention,

Fig. 2 is a vertical transverse section through the same on a line 2—2 of Fig. 1,

Fig. 3 is an enlarged vertical transverse section through one of the sides or walls of the hull.

In carrying out this invention, all of the walls and if desired the bottom of the hull are composed of an outer sheet metal skin or sheathing 1, an inner shell, skin or sheathing 2 and an intermediate shell 3, the several shells 1, 2 and 3 being composed of sheet metal, and each being made up of a plurality of plates of any desired size riveted or otherwise firmly secured together, each of the members 1, 2 and 3 being practically water-tight in itself.

The inner sheathing or shell 2 is fastened securely to the outer faces of the ribs or frame members 4 which may be of any desired shape or curvature according to the shape of the vessel or hull. These ribs or frames 4 are preferably made of steel and they are connected in transversely opposed pairs of metal ties or carlines 5 giving the necessary rigidity to the complete hull and

avoiding the spreading or collapsing of the same under excessive pressures both internal and external.

The outer shell or sheathing 1 has securely fastened to the inner face thereof by means of rivets or other suitable fasteners, steel bars 6 which extend in parallel relation to the ribs or frames 4. The bars 6 may be located at any desired distance apart and the frames or ribs 4 may also be located at any desired intervals. Tie bolts or rods 7 connect the outer and inner shells or sheathings and maintain the same in a fixed and spaced relation to each other, within the space 8 left between the members 2 and 3 there is a filling of concrete indicated at 9, the mass of concrete being preferably of such a consistency that it may be poured into the space 8 so as to completely fill said space and also fill any crevices caused by the formation of the hull to receive the tie rods and bolts hereinabove referred to.

As hereinabove stated, the bottom of the hull may be formed in the same manner as the sides thereof and where the hull is of the round bottom or dead rise type, the inner and outer shells together with the ribs or frame members and the bars 6 may be joined to the keel. The inside keel or keelson may likewise be formed in the same manner to comprise the inner and outer shells with the ribs, bars and the filling of concrete, the whole producing a hull structure which is water-tight, practically indestructible and which will resist the action of salt water and other elements.

The construction hereinabove described is adapted to hulls of all kinds such as those of ships, barges and all marine vessels of any character whatsoever. The bulk heads, the bed for the engine, the bed for the boiler, and the housing for the propeller shaft may also be built up in the same manner of metal and concrete. The keelson may be embedded in concrete of sufficient thickness to lie flush with the top of the keelson thereby producing a sanitary and fire-proof structure. Greater cargo space is provided for and the several parts of the hull may be easily assembled and the entire structure completed at places where ordinary ship construction has hitherto been impracticable by reason of lack of facilities. The hull may of course be divided up into compartments and sub-compartments by utilizing the same general wall structure hereinabove described.

What is claimed is:

1. In marine hull construction, the combination of an inner metal sheathing, frame pieces to which said inner sheathing is fastened, an outer metal sheathing arranged in spaced relation to the inner sheathing, metal bars fastened to the inner surface of said outer sheathing and arranged transversely opposite and substantially parallel to the 10 inside frame members, tie bolts extending perpendicularly to and through the outer and inner sheathings and maintaining the same in a fixed and spaced relation to each other, and a filling of concrete between said 15 outer and inner sheathings.
2. In marine hull construction, the combination of an inner metal sheathing, frame pieces to which said inner sheathing is fastened, an outer metal sheathing arranged in 20 spaced relation to the inner sheathing, an intermediate shell between and in spaced relation to said inner and outer sheathings, metal bars fastened to the inner surface of said outer sheathing and arranged trans- 25 versely opposite and substantially parallel to the inside frame members, tie bolts ex-
3. In marine hull construction, the combination of an inner metal sheathing, frame pieces to which said inner sheathing is fastened, an outer metal sheathing arranged in 30 spaced relation to the inner sheathing, an intermediate shell between and in spaced relation to said inner and outer sheathings, metal bars fastened to the inner surface of said outer sheathing and arranged trans- 35 versely opposite and substantially parallel to the inside frame members, tie bolts extending perpendicularly to and through the outer and inner sheathings and also through the intermediate shell, a filling of concrete 40 between said intermediate shell and the inner sheathing, and tie members extending transversely across the hull and connecting oppositely located frame members. 45

In testimony whereof I affix my signature. 50

THOMAS FENWICK.
